Des. 188,572
Patented Aug. 9, 1960

188,572

WALL MOUNTED WATER COOLER OR THE LIKE

Herman B. Castillo, Detroit, Mich., assignor to Temprite Products Corporation, Birmingham, Mich., a corporation of Michigan

Filed Apr. 20, 1959, Ser. No. 55,568

Term of patent 14 years

(Cl. D67—4)

Figure 1 is a reduced perspective view of a wall mounted water cooler or the like embodying my new design;

The dominant features of the design reside in the parts shown in full lines.

I claim:

The ornamental design for a wall mounted water cooler or the like, substantially as shown and described.
